UNITED STATES PATENT OFFICE

GEORGE H. SAUERMANN, OF MIDDLETON, CONNECTICUT, ASSIGNOR TO THE RUSSELL MANUFACTURING COMPANY, OF MIDDLETON, CONNECTICUT, A CORPORATION OF CONNECTICUT

VENTILATED WEBBING

Application filed July 12, 1930. Serial No. 467,403.

This invention relates to fabrics and is concerned more particularly with an elastic fabric or webbing especially suitable for incorporation in garments by reason of its being so constructed as to afford ventilation and elasticity both warp-wise and filling-wise.

Elastic webbing is now used extensively in the manufacture of such garments as garters and the like, and it has also been employed 10 in pajama trousers to replace the usual drawstring. Webbing for such purposes is preferably relatively wide so that it will not cause discomfort to the wearer due to binding but such wide webbing has the disadvantage that 15 it fits the body of the wearer snugly over a substantial surface from which it cuts off air circulation.

The present invention is accordingly directed to the provision of an elastic webbing 20 which may be of sufficient overall width to prevent uncomfortable binding and affords ventilation so that discomfort from this source is overcome. At the same time, the new webbing may have the same resistance to 25 stretch as an ordinary webbing of the same overall width.

The new fabric includes a plurality of webs of any suitable or preferred weave lying side by side with a space between and connected 30 by a strand which has spaced portions along its length secured to the webs alternately, and intermediate portions which extend across the space. Preferably the portions of the strand connected to the webs are woven there- 35 in and held in place by filling or weft strands.

For a better understanding of the invention, reference may be had to the accompanying drawings, in which Fig. 1 is a plan view of the new fabric in normal condition, and 40 Fig. 2 is a similar view showing the fabric stretched.

The fabric as illustrated is made up of a pair of webs 10a and 10b, each of which includes non-elastic warp strands 11, elastic 45 warp strands 12, and filling strands 13. In the construction illustrated there are four elastic warp strands incorporated in each web, one along each edge and two in the body of the web but this arrangement is only one 50 of many which may be employed, although it

is preferable to have elastic warp strands at the edges of the webs.

The webs lie side by side with a space between and are secured together by a connecting element 14 which may take the form of an elastic or non-elastic warp strand. This strand has spaced portions 14a along its length which are secured alternately to the webs and intermediate portions 14b which extend across the space between the webs. 55

Preferably the portions 14a of the strand are woven into the webs. For this purpose each web is woven with a separate shuttle and during the weaving, the warps are stretched taut as indicated in Fig. 2 with the strand 14 lying between the warp strands which are to lie at the adjacent edges of the webs. While a portion of the fabric is being woven, the strand 14 is connected to the web 10a by filling strands 13a which extend 60 around the strand so that it is woven into web 10a. After a suitable length of the strand 14 has been thus secured to one web, a similar length is connected to the web 10b in a similar manner. When the fabric is allowed to shrink, spaced portions 14a of the strand are connected to the webs in alternation, while the intermediate portions 14b extend across the space between the webs. 65

The new fabric has any desired overall 70 width and, while it has been illustrated as made up of two webs and a single connecting strand, it is apparent that it may include additional webs, connected together in the manner described. 75

I claim:

1. A fabric which comprises a pair of webs lying side by side with a space between them, and a connecting warp strand having spaced portions woven into the webs in alternation, 80 the intermediate portions of said strand extending across said space, said space being free of filling strands and said webs and strand all adapted to lie in a single plane.

2. A fabric which comprises a pair of webs 85 lying side by side with a space between them, and a connecting warp strand having spaced portions woven into the opposed edges of the webs in alternation, the intermediate portions of said strand extending across said 90

space, said space being free of filling strands and said webs and strand all adapted to lie in a single plane.

3. A fabric which comprises a pair of webs

5 lying side by side with a space between them, each web comprising warp and filling strands, and a connecting warp strand having spaced portions connected to the webs in alternation by means of filling strands there-
10 of, the intermediate portions of said strand extending across said space, said space being free of filling strands and said webs and strand all adapted to lie in a single plane.

4. A fabric which comprises a pair of elas-

15 tic webs lying side by side with a space be-
tween them, and a connecting warp strand having spaced portions woven into the webs in alternation and intermediate portions ex-
20 tending across said space, said space being free of filling strands and said strand having substantially the same length as the fab-
ric when the latter is stretched to its limit.

5. A fabric which comprises a pair of elas-
25 tic webs made up of elastic and non-elastic
warp strands and filling strands, said webs lying side by side in a plane with a space be-
tween the adjacent edges thereof, and a con-
necting warp strand having spaced portions along its length secured alternately to said
30 edges of the webs by filling strands thereof, and intermediate portions extending across said space, said space being free of filling strands.

6. A fabric which comprises a pair of elas-
35 tic webs made up of elastic and non-elastic
warp strands and filling strands, said webs lying side by side in a plane with a space be-
tween the adjacent edges thereof, and a con-
necting warp strand having spaced portions
40 along its length secured alternately to said
edges of the webs by filling strands thereof, and intermediate portions extending across said space, said space being free of filling strands and said strand having a length sub-
45 stantially the same as said non-elastic warp
strands.

7. A fabric which comprises a pair of elas-
tic webs lying side by side with a space be-
tween the adjacent edges thereof, each web
50 including elastic and non-elastic warp
strands and filling strands, and a connecting
warp strand having spaced portions along its
length lying along said adjacent edges of said
webs in alternation and held thereto by filling
55 strands thereof, the intermediate portions of
said connecting strand extending across said
space, said space being free of filling strands.

8. A fabric which comprises a pair of elas-
tic webs lying side by side with a space be-
60 tween the adjacent edges thereof, each web
being made up of non-elastic warp strands,
filling strands and elastic warp strands, at
least one of said elastic warp strands lying
65 along the inner edge of each web, and a con-
necting warp strand having spaced portions

along its length lying in contact alternately along said adjacent edges of said webs with said elastic warp strands and secured to said webs, said space between the webs being free of filling strands.

9. A fabric which comprises a pair of webs
70 lying side by side with a space between them
and a connecting warp element having spaced
portions along its length secured alternately
75 to said webs and intermediate portions ex-
tending across said space, said space being
free of filling strands and said webs and
strand all adapted to lie in a single plane.

10. A fabric which includes a pair of webs
80 lying side by side with a space between them
and connected by a warp element extending
across said space at spaced points, said space
being free of filling strands and said webs
and strand all adapted to lie in a single plane.

11. A fabric which includes a pair of webs
85 lying side by side with a space between them
and secured together by connecting warp
means extending across said space at spaced
points alternately in opposite directions, said
90 space being free of filling strands and said
webs and strand all adapted to lie in a single
plane.

12. A fabric which comprises a pair of webs
95 lying side by side with a space between them
and connected by a warp strand extending
across said space at intervals, said webs be-
ing longitudinally extensible and said fabric
100 being transversely extensible, and said space
being free of filling strands and said webs and
strand all adapted to lie in a single plane.

13. A fabric which comprises a plurality
105 of webs lying side by side with spaces between
them, adjacent webs being connected by a
warp strand extending across said space at
intervals, and each of said spaces being free
110 of filling strands and said webs and strand all
adapted to lie in a single plane.

In testimony whereof I affix my signature.
GEORGE H. SAUERMANN.
